UNITED STATES PATENT OFFICE

SAMUEL GROSSMAN, OF NEW YORK, N. Y., ASSIGNOR TO DAVID KLEBANOFF AND SAMUEL GROSSMAN, COPARTNERS, DOING BUSINESS AS KLEBANOFF AND GROSSMAN, OF NEW YORK, N. Y.

DESIGN FOR A FINGER RING

Application filed February 21, 1929. Serial No. 30,168. Term of patent 3½ years.

To all whom it may concern:

Be it known that I, SAMUEL GROSSMAN, a citizen of the United States of America, residing at city of New York, county of Bronx and State of New York, have invented a new, original, and ornamental Design for Finger Rings, of which the following is a specification, reference being had to the accompanying drawings, forming part thereof.

Fig. 1 is a side elevation thereof;

Fig. 2 is a top plan view of a ring embodying the new design; and

Fig. 3 is an edge view thereof.

I claim:

The ornamental design for a finger ring as shown.

In witness whereof I have signed this specification this 20th day of February, 1929.

SAMUEL GROSSMAN.
